UNITED STATES PATENT OFFICE

149,428

DESIGN FOR A SPOON OR OTHER ARTICLE
OF FLATWARE

Isadore A. Lipman, Meriden, Conn., assignor to The Ellmore Silver Co., Inc., Meriden, Conn., a corporation of Connecticut

Application December 30, 1947, Serial No. 143,431

Term of patent 14 years

(Cl. D54—12)

To all whom it may concern:

Be it known that I, Isadore A. Lipman, a citizen of the United States, residing in the city of Meriden, county of New Haven, and State of Connecticut, have invented a new, original, and ornamental Design for a Spoon or Other Article of Flatware, of which the following is a specification, reference being had to the accompanying drawing, forming a part thereof.

The essential features of my design reside in the handle portion of the spoon shown in full lines.

I claim:

The ornamental design for a spoon or other article of flatware, as shown and described.

ISADORE A. LIPMAN.
